(57) **CLAIM**

The ornamental design for a bag, as shown and described.

DESCRIPTION

FIG. 1 is a front perspective view of a bag showing our new design;

FIG. 2 is a rear perspective view thereof;

FIG. 3 is a bottom view thereof; and,

FIG. 4 is a partial enlarged view of FIG. 1.

The dotted lines shown within the solid lines in FIGS. 1-4 represent stitching.

The dash-dot broken lines in FIG. 4 enclose portions of the claimed design that are illustrated in enlargements and form no part of the claimed design.
